(57) **CLAIM**

The ornamental design for a notebook computer, as shown
and described.

DESCRIPTION

FIG. 1 is a perspective view of a notebook computer
showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the portion, labeled '8' of FIG.
1;

FIG. 9 is a front view thereof with the display opened;

FIG. 10 is a rear view thereof with the display opened;

FIG. 11 is a left side view thereof with the display opened;

FIG. 12 is a right side view thereof with the display opened;

FIG. 13 is a top view thereof with the display opened;

FIG. 14 is a bottom view thereof with the display opened;

FIG. 15 is a perspective view thereof with the display
opened at a large angle relative to the host;

FIG. 16 is a perspective view thereof with the display
opened at a small angle relative to the host; and,

FIG. 17 is another perspective view thereof with the display
opened at the small angle relative to the host.

The dashed broken lines illustrate portions of the notebook
computer and form no part of the claimed design. The
dot-dash broken lines define the bounds of the claimed
design and form no part thereof.

1 Claim, 15 Drawing Sheets
